OIL COOLER

Charles L. McCuen, Lansing, Mich.

Application February 23, 1932, Serial No. 594,427

13 Claims. (Cl. 184—6)

This invention relates to novel means for cooling an internal combustion engine and the lubricating oil employed therein; and it resembles the invention described in the Schittke Patent No. 5 1,909,637 which was issued on May 16, 1933, in that it may include means for operating an oil pump by a direct and co-axial extension of a cam shaft,—said pump and an oil cooler being preferably carried in an external and accessible position by a housing which extends over a sprocket gear; but, in the present invention, the oil pump is regularly fed, in a manner enabling it ordinarily to serve as a booster pump, through said cam shaft,—being included in a closed loop 10 and associated with a novel switch device in a manner which renders the maintenance of circulation of oil through said loop dependent upon the frictional resistance therein. A second or 15 service pump is so employed, in connection with the mentioned switch device, as to assure a supply of oil to the engine bearings at all times.

In case it is desired to provide for the direct operation of the engine water pump which circulates water through the oil cooler from a 20 fan shaft of the engine, the body of said pump (and/or that of said oil cooler) may be cast integral with said gear housing; and, to provide the mentioned switch device, one of the bearings of the cam shaft may include or be surrounded by an apertured shell element about 25 which and within which annular passages are provided,—the construction here referred to being such as to assure flow of oil through said shell in one direction only, or in neither direction, 30 according to the conditions existing in the mentioned loop.

The mentioned oil cooler is preferably of the Ramsaur-Chase type (similar to that described and claimed in the Ramsaur and Chase Patent 40 No. 1,902,970 which was issued on March 28, 1933), in that it may include a set of cylindrical tubes having "hex" ends through which water may descend while the oil to be cooled is advanced transversely between said tubes; but, in the present instance, the oil is not permitted or obliged to descend into an oil pan (wherein it might be unduly re-heated in advance of use) but is fed, through said switch device, into a conduit leading to the engine bearings.

50 Other objects of the present invention, including the employment of a single main casting to provide a gear housing, the outer walls of an oil cooler, an outer wall of a water pump and water-delivery passages, may be best appreciated from 55 the following description of an illustrative em-

bodiment thereof, taken in connection with the appended claims and the accompanying drawings.

Figure 1 is a longitudinal, vertical sectional view showing parts of an engine equipped with an embodiment of the present invention;—oil pump parts being broken away to slightly different planes.

Figure 2 is a view, taken substantially as suggested by the broken line 2—2 of Figure 1, but with parts in elevation and other parts cut away to a deeper level.

Figure 3 is a horizontal sectional view, taken substantially as indicated by the line 3—3 of Figures 1 and 2 but showing the core of the oil 15 cooler mainly in plan.

Figure 4 is an exploded perspective view of the main casting and oil cooler assembly shown in the preceding figures.

Figure 5 is a more or less diagrammatic view 20 of an engine lubricating system utilizing the present invention.

Figure 6 is a vertical sectional view, taken substantially as indicated by the lines 6—6 of Figures 1 and 5.

Referring first to conventional parts of that embodiment of the present invention which has been selected for purposes of illustration, an engine block 11 is shown as having secured therebelow an oil pan 12 and as comprising (together 30 with numerous usual parts) a crank shaft 13, and a cam shaft 13',—the latter being driven from the former by means of a sprocket chain and gears 14, 14'. Gear 14' is shown as enclosed within a housing 15, secured at the front of the 35 block 11; and this housing may be formed integral with or support essential elements of an engine and oil cooling system,—such as an oil pump O. P., an oil cooler O. C. and/or a water pump W. P. or parts thereof.

To drive the oil pump O. P., when positioned as shown, cam-shaft 13' may carry, by means of screws 16 (shown as serving also to retain the gear 14') a plate 17 having a non-circular opening at 18,—the parts last referred to being employed to transmit rotation to an extension shaft 19, interfitting within said opening. The shaft 19 is shown as extending through a bearing 20 integral with an oil pump casing 21,—the latter being seated in a suitable opening 22 in the front 50 wall 23 of the gear housing 15 provided by the main casting above referred to. This oil pump may comprise, in addition to the shaft 19 (herein shown as hollow and as adapted to provide a normal oil feed passage 24, co-axial with a main 55

oil conduit 25 in the shaft 13') gears 26 and 27, in casing 21, respectively carried by the extension shaft 19 and by a parallel short shaft 28; and the pumped oil may normally exit from the 5 pump O. P. through a pipe 29, connected with the oil cooler O. C. or with any desired oil-conditioning unit.

As may be best appreciated by an examination of Figures 1, 5 and 6, a preferred type of lubricating system utilizing mentioned parts may include not only the mentioned main oil conduit 25, preferably provided in shaft 13' and fed by a service pump O. P., in the oil pan 12, but also a branch or distribution conduit 31, leading to 15 any desired additional bearings 32,—including, for example, those which may support the crank-shaft 13; and said system is preferably of figure-8 form,—the oil pump O. P. and oil cooler being included in a loop conduit 33, through 20 which the cooled or otherwise conditioned oil is normally advanced to a switch device S. D., now to be described.

The foremost bearing of the shaft 13' is shown 25 as comprising a shell-element 34 having a single aperture 35 therein, this shell being surrounded by a fixed annulus 36 which provides a peripheral channel or groove 37, adapted to receive oil from the conduit 33 or through the aperture 35; and the shaft 13' is shown as provided, within the 30 shell 34, with a corresponding peripheral channel 38,—this being in communication with the main conduit 25 by way of a plurality of radial passages 39. The construction here referred to is such that, assuming the output of the respective oil pumps O. P. and O. P', to be equal, oil advanced through the main conduit 25 may normally continue through the oil-conditioning loop 33, thence advancing through the channel 37, exterior to the shell 34, into the branch conduit 40 31, or its equivalent; but said construction will be seen to be such that, in case of any stoppage in the loop conduit 33, oil advanced through the main conduit 25 may exit therefrom through the opening 35 in shell 34 directly into the branch 45 conduit 31,—assuring an adequate supply of oil to said branch conduit at all times.

The pumps O. P. and O. P' are preferably of 50 substantially equal capacity and driven at substantially the same rate; but, in order to obviate damage in case of stoppage in any part of the oil-conditioning loop conduit 33, or its equivalent, the pump O. P may be provided with novel means rendering the efficiency thereof dependent upon the frictional resistance encountered by the pumped oil in advancing through said loop circuit. For example, a cover element 40 of said pump may provide not only a passage 41 through which oil may normally advance from the interior of the extension shaft 19 into the feed 55 chamber of said pump, but also a normally closed by-pass opening 42, conditionally establishing a direct communication between a feed chamber and a delivery chamber of said pump. The opening 42 may be normally closed by a ball-valve element 43 and an adjustable compression spring 44 within a threaded thimble 45,—the latter being shown as received within a suitable boss 46 upon the cover element 40; and it will be understood that whenever the pressure within the delivery 60 chamber of the pump O. P. rises above a predetermined value, as by reason of any clogging of the cooler O. C., a by-passing of the pumped oil diminishes the efficiency of said pump O. P. to any desired degree. A spring 48 is shown as

seated between a shoulder 49, provided within the end of the shaft 13', and a shoulder 50 (provided upon the inner end of the extension shaft 19) and as serving yieldably to maintain these parts in a non-chattering co-axial relationship; and lubricating passages 51 are shown as extending through the shaft 19 to the bearing 20; but the exact details of the construction here referred to will be understood to be of relatively minor importance.

The cooler O. C. preferably comprises, in addition to a back wall 52 and side walls 59, 59' provided by the main casting, a removable front plate 54. The latter is shown as secured to the main casting by bolts or screws 55 and as adapted, in turn, to support an oil cooler core unit removable therewith and connected into the oil conditioning loop conduit 33 by means of threaded fittings 56, 56'. The oil cooler core unit may comprise any suitable number of parallel tube elements 57, so disposed as to permit cooling water to descend therethrough while providing also for the lateral advance of oil therebetween. For example, a pair of corrugated plate elements 58, 58' may so engage the "hex" ends of the front and back rows of the tubes 57 as to maintain the same in assembled relationship, ends of said plates being received within flanges upon oil header elements 53, 53'—to which the mentioned fittings 56, 56' are secured; and, if desired, abutting edges of mentioned elements being soldered together, additional reinforcement may be provided by means such as a binding collar or collars 60. The latter, if provided, may be L-shaped in cross sectional outline and may interfit with the upper and/or lower portions of the mentioned plates 58, 58' and/or headers 53, 53' and/or "hex" ends of the tubes 57. This construction will be seen to be such as to permit the cooling water, from any desired source, to advance not only through the described unit but also, in a suitable film, externally thereof.

The cooling water circuit employed herein may be substantially the same as that described in the mentioned Schittke patent. That is to say, the mentioned main casting may upwardly terminate in a substantially cylindrical portion 61, adapted to serve as an exterior wall element receiving the rotor 62 of water pump W. P.—said rotor being shown as secured upon and driven through a shaft 63. This shaft may carry also an engine cooling fan 64 and the ends of said shaft may be received in a bearing organization 65, received within and secured to the cylindrical portion 61 of said main casting. Water at a suitable low (or high) temperature may enter the pump W. P. through a tubulation 66; and, in case it is to be advanced from the oil cooler O. P. directly to the engine block 11, such advance may be effected through passages 67. These are shown as provided in said main casting and they may open directly into the jacket provided by said block.

Except as features thereof may be used for 65 heating effects when required, it will be understood that the described system aims not only at lubrication but at cooling,—cooling effect being through both the water and the oil. When the temperature of the oil is so low as to require no cooling, the resistance of the cooler may be such as to reduce or obviate flow therethrough. Otherwise, so long as the cooler is not clogged, the two oil pumps cannot operate individual circuits because, to do this, oil would have to pass 70

- through the opening 35, in the shell of described switch device S. D., in opposite directions at the same time. If the two oil pumps vary in capacity or in pumping effect, there will be a flow through 5 said opening 35 in one direction or the other; but this flow will be proportional to the difference between the mentioned pumping effects, and it may be very small in comparison to the total amount of oil handled. No manual valve need be 10 provided in loop conduit 33, for even a partial clogging of the oil cooler, causing a partial flow past the valve 43, will cause a corresponding flow outward through the shell opening 35 to assure a supply of oil to the bearings 32, through the 15 branch conduit 31, under all conditions. It will thus be seen that the described system normally includes a lubricating circuit of figure-8 form, in which the described switch device S. D. serves for the connection of an oil-conditioning loop 20 conduit with a main conduit, and in which the main conduit and a branch conduit together comprise a larger loop which includes the engine bearings and the oil pan,—suitably tempered oil being always advanced therethru.
- 25 Although the foregoing description has included complete details of but one embodiment of the present invention, it should be understood that not only are there features thereof which might be independently employed but also that numerous modifications, additional to those suggested herein, might easily be devised by workers skilled in the lubrication arts and familiar with the foregoing,—all without departure from the 30 scope of the present invention.
- 35 I claim:
1. In a lubricating system for internal combustion engines: a main oil conduit; a switch device having an outlet which leads to bearings to be lubricated; and an oil-conditioning loop so connected with said main oil conduit, through said switch device, as normally to deliver conditioned oil to said outlet leading to bearings.
  2. In a lubricating system for internal combustion engines: a main oil conduit; a switch device having an outlet which leads to bearings to be lubricated; and an oil-conditioning loop so connected with said main oil conduit, through said switch device, as normally to deliver conditioned oil to said outlet,—each of said conduits being 40 provided with a pump, and the pump in said oil-conditioning loop being adapted normally to function as a booster pump.
  3. In a system of the general character described: a switch device in the form of an apertured sleeve surrounding a hollow member providing a main conduit,—an annular channel being provided within the sleeve in communication with said conduit and an additional channel being provided without the sleeve and in communication with the first mentioned channel and additional conduits in communication with the last-mentioned channel.
  4. In a lubricating system, a lubricant supply conduit, a lubricant service conduit, a lubricant conditioning conduit through which lubricant flows at a rate which varies with its condition, means connecting the lubricant supply conduit, the lubricant service conduit and both ends of the lubricant conditioning conduit and affording 45 uninterrupted communication therebetween, and means for advancing lubricant from the lubricant supply conduit to the lubricant service conduit through the lubricant conditioning conduit, including a pump in the lubricant supply conduit and a pump in the lubricant conditioning conduit, and means rendering the effectiveness of the pump in the lubricant conditioning conduit dependent upon 50 the condition of the lubricant.
  5. In a lubricating system, a lubricant supply conduit, a lubricant service conduit, a lubricant conditioning conduit through which lubricant flows at a rate which varies with its condition, 55 means connecting the lubricant supply conduit to the lubricant service conduit and to one end of the lubricant conditioning conduit and the other end of the lubricant conditioning conduit to the lubricant service conduit and affording uninterrupted communication therebetween, and means for advancing lubricant from the lubricant supply conduit to the lubricant service conduit through the lubricant conditioning conduit.
  6. In a lubricating system, a lubricant supply conduit, a lubricant service conduit, a lubricant conditioning conduit through which lubricant flows at a rate which varies with its condition, 60 means connecting the lubricant supply conduit to the lubricant service conduit and to one end of the lubricant conditioning conduit and the other end of the lubricant conditioning conduit to the lubricant service conduit and affording uninterrupted communication therebetween, and means for advancing lubricant from the lubricant supply conduit to the lubricant service conduit through the lubricant conditioning conduit, including a pump in the lubricant supply conduit and a pump in the lubricant conditioning conduit, and means rendering the effectiveness of the pump 65 in the lubricant conditioning conduit dependent upon the condition of the lubricant.
  7. In a lubricating system, a lubricant supply conduit, a lubricant service conduit, a lubricant conditioning conduit through which lubricant flows at a rate which varies with its condition, means connecting the lubricant supply conduit to the lubricant service conduit and to one end of the lubricant conditioning conduit and the other end of the lubricant conditioning conduit to the lubricant service conduit and affording uninterrupted communication therebetween, and means for advancing lubricant from the lubricant supply conduit to the lubricant service conduit through the lubricant conditioning conduit, including a pump in the lubricant supply conduit and a pump in the lubricant conditioning conduit, and means rendering the effectiveness of the pump 70 in the lubricant conditioning conduit dependent upon the condition of the lubricant.
  8. In a lubricating system, a lubricant supply conduit, a lubricant service conduit, a lubricant conditioning conduit through which lubricant flows at a rate which varies with its condition, means connecting the lubricant supply conduit to the lubricant service conduit and to one end of the lubricant conditioning conduit and the other end of the lubricant conditioning conduit to the lubricant service conduit and affording uninterrupted communication therebetween, and means for advancing lubricant from the lubricant supply conduit to the lubricant service conduit through the lubricant conditioning conduit, including a pump in the lubricant supply conduit and a pump in the lubricant conditioning conduit, and means rendering the effectiveness of the pump 75 in the lubricant conditioning conduit dependent upon the condition of the lubricant.
  9. In a fluid transfer system, a fluid supply conduit, a fluid service conduit, a fluid conditioning conduit through which fluid flows at a rate

the fluid supply conduit, the fluid service conduit and both ends of the fluid conditioning conduit and affording uninterrupted communication therebetween, and means for advancing fluid from the fluid supply conduit to the fluid service conduit through the fluid conditioning conduit.

11. In a fluid transfer system, a fluid supply conduit, a fluid service conduit, a fluid conditioning conduit through which fluid flows at a rate which varies with its condition, means connecting the fluid supply conduit to the fluid service conduit and to one end of the fluid conditioning conduit and the other end of the fluid conditioning conduit to the fluid service conduit and affording uninterrupted communication therebetween, means for advancing fluid from the fluid supply conduit to the fluid service conduit through the fluid conditioning conduit, including a pump in the fluid supply conduit and a pump in the fluid conditioning conduit, and means rendering the effectiveness of the pump in the fluid conditioning conduit dependent upon the condition of the fluid.

12. In a fluid transfer system, a hollow shaft which constitutes a conduit, an annular member which encircles the hollow shaft, a conduit con-

nected to the annular member, orifices in the hollow shaft and the annular member affording communication between the mentioned conduits, and a passage which interconnects the mentioned conduits.

13. In a fluid transfer system, a hollow shaft which constitutes a conduit, an annular member which encircles the hollow shaft, an annular member which encircles the first-specified annular member, an annular groove between the specified annular members, an annular groove between the first-specified annular member and the hollow shaft, an orifice in the hollow shaft which affords communication between the mentioned conduit and the second-specified annular groove, an orifice in the first-specified annular member which affords communication between the specified annular grooves, a conduit which communicates with the first-specified annular groove near the second-specified orifice, and a conduit whose ends communicate with the first-mentioned conduit and the first-specified annular groove at a distance from the second-specified orifice.

CHARLES L. MCCUEN. 25

CERTIFICATE OF CORRECTION.

Patent No. 2,067,721.

January 12, 1937.

CHARLES L. McCUEN.

It is hereby certified that error appears in the above numbered patent requiring correction as follows: In the grant, line 6, title of invention, for "AIR COOLERS" read OIL COOLERS; page 3, second column, line 75, claim 10, after the word "rate" insert which varies with its condition, means connecting; and that the said Letters Patent should be read with these corrections therein that the same may conform to the record of the case in the Patent Office.

Signed and sealed this 16th day of March, A. D. 1937.

(Seal)

Henry Van Arsdale
Acting Commissioner of Patents.
